CLAIM

The ornamental design for the cell phone carrier, as shown and described.

DESCRIPTION

FIG. 1 illustrates a top, front, right-side perspective view of a cell phone carrier of my new design in an open position. FIG. 2 illustrates a bottom, rear, left-side perspective view thereof.

FIG. 3 illustrates a front elevation view thereof.

FIG. 4 illustrates a rear elevation view thereof.

FIG. 5 illustrates a right-side elevation view thereof.

FIG. 6 illustrates a left-side elevation view thereof.

FIG. 7 illustrates a top plan view thereof; and,

FIG. 8 illustrates a bottom plan view thereof.

That portion of the carrier shown in phantom in FIGS. 1 to 4, 7 and 8 is not part of the design sought to be patented and is provided for environmental purposes only.
